UNITED STATES PATENT OFFICE.

ENOCH OHNSTRAND, OF SYRACUSE, NEW YORK, ASSIGNOR TO U. S. STEEL FURNITURE COMPANY, OF SYRACUSE, NEW YORK, A CORPORATION OF NEW YORK.

TOP FOR FURNITURE.

1,168,106.

Specification of Letters Patent. Patented Jan. 11, 1916.

Application filed September 7, 1912. Serial No. 719,246.

To all whom it may concern:

Be it known that I, ENOCH OHNSTRAND, of Syracuse, in the county of Onondaga and State of New York, have invented a new and useful Improvement in Tops for Furniture, which improvement is fully set forth in the following specification and shown in the accompanying drawings.

The present invention relates to furniture tops such as that employed on tables, desks and other articles having flat top surfaces, and an object of this invention is to provide a simple and effective means for securing a thin veneer covering upon such tops.

Another object of the invention is to provide for protecting the edges of the veneer covering, while at the same time preventing the formation of crevices which will collect dirt, dust and the like.

Still another object of the invention is to provide a sheet metal top with a covering, the parts being so constructed that a wooden top is simulated.

To these and other ends the invention consists of certain parts and combinations of parts, all of which will be hereinafter described and more particularly pointed out in the appended claims.

In the drawings: Figure 1 is a central vertical section through the top showing the top covering being introduced upon the base of the top; Fig. 2 is an enlarged sectional view of the top showing the covering in place; Fig. 3 is a detail view of a portion of the blank from which one of the top plates is formed; Fig. 4 is a vertical section through another embodiment of the invention; and Fig. 5 is a detail vertical section through still another embodiment of the invention.

In carrying out this invention, the top may be supported upon a frame 1 in any suitable manner, so as to project beyond the same.

In the embodiment shown in Figs. 1 to 3, the top comprises a base formed of two sheet metal plates 2 and 3 supported one upon the other and riveted or otherwise secured together as at 4. The plate 3 may be formed from a rectangular blank such as shown in Fig. 3, notched at its corners at 5 and bent beyond the supporting frame and between the notches downwardly, outwardly and upwardly to provide channels 4 along the edges of the plate, the walls of the

notches 5 being welded together after the channels are formed so that one continuous and marginal groove is formed. The outer wall 6 of this groove extends above the top surfaces of the plates 2 and 3 and has its free edge turned inwardly and reduced to provide substantially a sharp or knife edge. The plate 2 has its edges projecting over the groove or channel 4 and lying in proximity to the wall 6 of said groove.

The covering for the top is in the form of a thin sheet or veneer 8 of suitable material. In the present instance, linoleum is employed. I have found that linoleum is an ideal covering for furniture tops. It will not absorb ink, is not readily injured and, as it may be readily washed, can be kept in a clean and sanitary condition. It may be made of any thickness but I prefer to use that which is about one-fourth of an inch thick. Preferably, the upper corners of this covering are cut away or rounded at 9, so that it will more readily coöperate with the inwardly turned sharp edges 7.

To place the covering 8 in position on the base it is bulged upwardly at its center so as to permit its edges to be received within and below the upper edges of the walls 6, cement being first applied to the upper face of the plate 2. When the covering is flattened, its edges 9 will move outwardly and beneath the inwardly turned portions of the wall 6, forcing the knife edges 7 slightly into the edges of the linoleum, as shown in Fig. 2, this being due to the fact that the curve of the inwardly turned portions is slightly different from the curve of the rounded portions 9. In this way, the knife edge 7 penetrates, to a slight degree, the edges of the covering and prevents the formation of crevices in which dirt and the like will collect, while at the same time, overhanging the edges of the covering and clenching or holding it in position. The plate 2 is provided in order to support the edges of the covering located over the channels 4.

In order to bulge the center of the covering for fitting the same to the base the two plates 2 and 3 are provided with alined or registering openings through which a rod 11 or other instrument may be introduced to engage the under surface of the covering 8 to produce the bulging action.

In the embodiment shown in Figs. 4 and

5, only a single top plate 3^a is employed and is secured to the frame 1 so as to project beyond the same. Instead of simulating the thickness of wood, by providing a channeled portion as in Figs. 1 and 2, this may be effected by bending the edges of the top downwardly or laterally with reference to the plane of the top as at 12, thence inwardly as at 13, and finally upwardly as at 14. 10 The retaining means embodies separate strips 15 which have their lower edges turned inwardly at 16 to coöperate with the portions 13 and their upper edges turned inwardly at 17 and provided with knife edges 7, as in the embodiment shown in Figs. 1 to 3. The strips may be riveted to the top as at 18 or may have integral projections 19 which are threaded and passed through openings in the portions 12, their 15 inner ends being engaged by nuts 20 as in Fig. 5.

In the embodiment shown in Figs. 4 and 5, the linoleum veneer is placed upon the top plate 3^a before the retaining means are 20 attached to said top plate. When these retaining plates are secured in place, their upper knife or sharp edges 7 are forced into the linoleum or veneer in the same manner as that disclosed in Figs. 1 and 3. 25 From the foregoing, it will be seen that there has been provided a top for tables, desks and other office furniture in which the covering is attached in a simple and effective manner without the provision of crevices 30 for the collection of dirt.

What I claim as my invention and desire to secure by Letters Patent is:

1. A top for furniture comprising a base provided with a central opening, a portion 40 surrounding the base and turned inwardly above the same, and a flexible covering resting upon said base with portions of its edges located beneath the inwardly turned portion, said covering being adapted to be 45 fitted to the base by bulging the same centrally by an instrument introduced through the central opening.

2. A top for furniture comprising a sheet

metal plate notched at its corners and bent between the notched portions, downwardly, 50 outwardly and upwardly, the upper free edges lying above the top surface of the plate, and a covering supported by said plate and confined within the free edges of the base. 55

3. A top for furniture comprising a base formed from a rectangular piece of sheet metal notched at its corners, the portions of the material between the notches being bent downwardly, outwardly and upwardly and 60 secured together at their ends, the upper edges of said upwardly extending portions lying above the top surface of the base and being turned inwardly and provided with a sharp edge, and a covering supported on 65 said base and having its edges firmly engaged below the upper face thereof by the sharp edges on the base.

4. A top for furniture comprising a sheet of material bent downwardly, outwardly 70 and upwardly near its edges, the extreme edges lying above the top surface of said sheet, a second sheet of material supported on the first named sheet and bridging the channels formed in the first named sheet, 75 and a sheet of pliable covering material resting upon the second named sheet to be supported by the latter over the channel and having its edges protected by the edges of the first named sheet. 80

5. A top for furniture comprising a sheet of material notched at its corners and bent between the notched portions downwardly, outwardly and upwardly to provide channels about the said sheet, the upper edge of 85 the upwardly-extending portion lying above the top surface of the said sheet, a sheet of pliable covering material supported within the upwardly extending portions to be protected at its edges by said portions 90 and means for supporting the edges of said pliable covering over said channels.
